US00D996125S

(12) **United States Design Patent** (10) **Patent No.:** **US D996,125 S**
Ito (45) **Date of Patent:** **** Aug. 22, 2023**

(54) **FRYING PAN**

(71) Applicant: **Ito-Casting Co., Ltd.**, Aichi (JP)

(72) Inventor: **Go Ito**, Aichi (JP)

(**) Term: **15 Years**

(21) Appl. No.: **35/514,240**

(22) Filed: **Oct. 1, 2021**

(80) **Hague Agreement Data**

Int. Filing Date: **Oct. 1, 2021**

Int. Reg. No.: **DM/216704**

Int. Reg. Date: **Oct. 1, 2021**

Int. Reg. Pub. Date: **May 13, 2022**

(30) **Foreign Application Priority Data**

Apr. 14, 2021 (JP) ..... 2021-300008 D

Primary Examiner — Messina L Smith

(57) **CLAIM**

The ornamental design for a frying pan, as shown and described.

DESCRIPTION

1. Frying pan

1.1: Front

1.2: Left

1.3: Top

1.4: Bottom

1.5: Right

1.6: Cross sectional

The back side view of design No. 1 is omitted because it is a mirror image of the front side view of corresponding design; reproduction 1.6 is a cross sectional view taken along the 1.6-1.6 line shown in the reproduction 1.3.

1 Claim, 6 Drawing Sheets
